FIG. 5.

FIG. 4.

BY

Wilbert Lucas.
Gerald Baldwin
ATTORNEY.

UNITED STATES PATENT OFFICE.

WILBERT LUCAS, OF DETROIT, MICHIGAN.

ORTHOPEDIC SUPPORT FOR SHOES.

Application filed March 14, 1925. Serial No. 15,439.

To all whom it may concern:

Be it known that I, WILBERT LUCAS, a subject of the King of Great Britain, residing at Detroit, in the county of Wayne and State of Michigan, have invented new and useful Improvements in Orthopedic Supports for Shoes, of which the following is a specification.

I am aware that at the present time a number of devices are manufactured and sold for this purpose, but they usually consist of one of two types. Firstly, a bandage, which in order to afford support to the underside of the foot has to be tightened to such a degree as to interfere with the wearer's circulation, and which also has a detrimental effect on the small bones in the upper side of the foot, sometimes even resulting in their displacement. Secondly, a rigid arch support, which exerts upward pressure under the astragalus, and which is not adjustable either as to the extent or transverse location of the upward pressure it exerts.

This invention aims to provide a flexible support held in position under the astragalus by an arrangement of straps so as to form a cradle. The straps, moreover, are so arranged as to fasten round the leg just above the ankle.

Another object of the invention is to provide a special pad for the shock absorbing fleshy portion of the sole of the foot immediately behind the front ends of the metatarsal bones.

With these and other objects in view, the invention consists in certain novel construction and combination of parts hereinafter more fully described with the aid of the accompanying drawings, and claimed.

Figure 1 shows a flexible support in its simplest form independently of a shoe.

Figure 2 is another view of the support shown in Figure 1.

Figure 3 illustrates a shoe provided with my orthopedic support.

Figure 4 is an inverted plan showing the flexible support, and method of attaching it to an insole.

Figure 5 is a perspective of the flexible support, showing its upturned sides, the method of corrugating the upper surface of the insole, and the more or less centrally located pad for the shock absorber.

Figure 6 depicts a modified form of construction.

Referring more particularly to the drawings, and to Figures 3, 4, and 5 therein, 1 designates a shoe the sides of which are provided with side portions 2, sewn to the upper as indicated at 3, and having their lower ends sewn between the upper and the sole. Within the shoe is the insole 4, through which longitudinal slots 5 are provided, and the central portion 6 is attached, as by glue, to the underside of the flexible support 7. The sides of the latter bear against the inside of the upper as shown in Figure 3. The straps 8, which at the front I usually make integral with the toe cap 10, extend rearwardly against the outside of the upper, enter the front openings 9 between the upper and the portions 2, bear against the underside of the support 7, are threaded through the slots 5, and cross each other substantially under the centre of the insole 4. The straps emerge again through the rear slots 9, pass through the loop 11 formed by the heel reinforcing piece 12, and then come forward again round the leg and one of the straps may be threaded through the loop 13 attached more or less centrally over the shoe fastening means as shown in the drawing; or, if desired, the loop 13 may be omitted and the straps merely fastened round the leg in proximity to the ankle.

As the straps are tightened they compel the flexible support 7 to hug the sides of the foot as well as the bottom, and the diagonal arrangement of straps is such that support is afforded under and around the whole of the arch. Moreover the amount of support furnished may be increased or diminished by tightening or loosening the straps. And again as the fastening of the straps occurs round the lower portion of the leg, pressure on the upper part of the foot is obviated. The insole 4 may be provided with an inseam 14 for attachment to a welt, so that the sole itself cannot be raised to any appreciable extent in the centre by the straps.

More or less centrally of the fore part of the support I provide a roughened surface 15 through which there are a plurality of holes 16, and between the roughened surface and the insole, padding may be arranged to the desired thickness; in this way I furnish support for the fleshy shock absorbing portion of the foot. The roughened surface tends to minimize, or completely prevent, movement of the foot over the sur-

face, and the holes 16 form vacuum cups to further assist in holding the foot thereon. Callouses are formed by the movement of the foot against the usual smooth surface 5 of the lining, so that the construction herein mentioned materially lessens the possibility of their development. For the same reason I generally supply corrugations 20 on the upper surface of the insole; these I usually 10 make with knife cuts.

Referring now to Figures 1 and 2, the flexible support 4^a is generally made of felt, or some other material which is soft and at the same time has a slightly rough surface, 15 and on the underside is a piece of leather indicated at 17. 18 indicates a longitudinal loop through which the strap 8^a passes. In this case the strap bears over the centre of the foot, passes diagonally under the support 20 and is again secured round the lower part of the leg. The holes 16^a tend to hold the foot from slipping on the surface of the support in the same way as the holes 16.

Figure 6 shows the application of the invention to turned shoes and stitch-downs, 25 wherein the insole only extends from the heel to the front of the instep. In this case I combine the insole and the supporting member as shown at 21, attach it towards the front and rear to the outer sole as shown 30 at 22 and 23, and arrange the diagonal straps 8 thereunder.

Obviously, gaps (not shown in the drawings) have to be left between the upper and 35 the insole to allow the straps to be adjusted through and under the insole.

It is believed that a clear conception of the invention may be had from the foregoing description, and it is understood that 40 the construction of the support is subject to such modifications as fall within the scope of the appended claims.

What I claim as my invention and desire 45 to secure by Letters Patent is:—

1. An orthopedic support comprising a flexible supporting member adapted to extend under the arch of the foot, and flanges on each side of said member, in combination with a diagonal arrangement of straps under the said member by which upward pressure of said member and inward pressure of 50 said flanges can be exerted to varying degrees, and a roughened pad on said supporting member with holes through its upper surface adapted to support the shock absorbing fleshy portion of the sole of the foot.

2. An orthopedic support for shoes comprising a flexible supporting member at-

tached to the top of an insole having longitudinal slots therethrough, and straps passing under said supporting member and through said slots.

3. An orthopedic support for shoes comprising a flexible supporting member adapted to support the arch of a foot, upwardly projecting sides on said supporting member, diagonal straps under said member, outer portions on the sides of a shoe, part of said straps extending between said outer portions 70 and the outside of the upper, a means for holding the forward ends of the straps on the outer surface of said shoe, and fastening means on the opposite ends of said straps adapted to be secured round the leg of the 75 wearer in proximity to the ankle.

4. An orthopedic support for shoes as described in claim 3, wherein the flexible supporting member is attached to an insole, and wherein longitudinal slots are provided 80 through said insole on each side of the point of attachment.

5. An orthopedic support for shoes as described in claim 3, wherein a roughened raised surface having a plurality of holes 85 therein is provided in that portion of the flexible supporting member adapted to rest under the fleshy shock absorbing portion of the sole of the foot.

6. An orthopedic support for shoes as described in claim 3 wherein the means for holding the front ends of the straps consists of making them integral with a toe cap.

7. An orthopedic support for shoes comprising a shoe having a toe cap with a strap extending rearwardly from each side thereof, side portions on each side of an upper between which and said upper part of said straps are located, a flexible supporting member having upwardly extending sides located within the upper, said straps crossing diagonally under said supporting member and being adapted to exert upward pressure thereon and also inward pressure on 105 said upwardly extending sides, in combination with a loop behind the heel of the shoe through which said straps are threaded, and fastening means at the ends of said straps adapted to be fastened round the leg of a 110 wearer.

8. An orthopedic support for shoes as described in claim 7, wherein longitudinal slots are provided in the insole, and the upper surface of said insole is attached to the 115 underside of the flexible supporting member between said slots.

WILBERT LUCAS.
